MAN'S UNDERGARMENT

Meyer Hochberg, Detroit, Mich.

Application July 16, 1951, Serial No. 236,897

2 Claims. (Cl. 2—224)

1

This invention relates to undergarments and, in particular, to men's underpants or shorts.

One object of this invention is to provide men's shorts having a loop of elastic material attached to the waistband and extending upward so as to hook over one of the lower buttons of the man's shirt so that it not only holds the shirt down but also holds the shorts up.

Another object is to provide men's shorts of the foregoing kind wherein the elastic loop is of elastic cord and wherein the loop is maintained by stitching which converges toward the top of the waistband, thereby preserving the loop without interfering with its length which gives it its maximum stretch, this construction providing the loop with a narrow neck which holds the loop around the neck of thread by which the button is attached to the shirt so that the loop will not come off the button when the wearer bends over.

Another object is to provide men's shorts wherein the free ends of the loop diverge in a V-shaped arrangement, the ends of which are secured by stitching or in any other suitable way to the waistband or adjacent portions of the shorts so that the loop is given greater stability and steadiness in contrast to that if its ends were arranged parallel to one another.

Another object is to provide men's shorts of the foregoing character wherein the loop throughout its lower part is covered by a cover strip which not only serves to conceal the free ends of the loop but also prevents stretching of the waistband at the point where the loop is attached.

Another object is to provide men's shorts of the foregoing character of the so-called boxer type having an elastic waistband which dispenses with buttons and also having the elastic loop anchored to the shorts at or below the waistband but extending upward above the waistband sufficiently to provide clearance for attachment to the shirt button, the thread of which serves as a bridge when the button with the loop slipped over it is inserted in the buttonhole of the shirt band.

Other objects and advantages of the invention will become apparent during the course of the following description of the accompanying drawings, wherein:

Figure 1 is a perspective view of a pair of shorts of the present invention shown in its position when worn, with the buttonhole unbuttoned to reveal the elastic loop slipped over the button;

Figure 2 is an enlarged fragmentary front ele-

2

vation of the portion of the shorts of Figure 1 adjacent the elastic loop with the cover strip broken away to show the mode of attaching the loop to the shorts; and

5 Figure 3 is a horizontal section taken along the line 3—3 in Figure 2, showing the construction of the shorts adjacent the loop and cover strip.

Referring to the drawings in detail, Figure 1 shows a pair of men's shorts, generally designated 10, of the so-called boxer type having an elastic waistband 11 equipped with the elastic loop device 12 of the present invention with the elastic loop 13 thereof shown as hooked over a lower button 14 of the wearer's shirt with the shirtband 15a carrying the buttonholes 16 unbuttoned and pulled aside in order to show the construction more clearly. The so-called boxer shorts are free from any buttons and have almost entirely displaced men's so-called button shorts as well as so-called union suits. For many years, men have been subject to the annoyance of having their shirts gradually pull out of their trousers at the waistband, giving a dishevelled appearance. The present invention with the elastic loop construction 12 not only holds the shirt down but also holds the shorts up, as well as giving the other advantages described above in the objects of the invention and the description of the use of the shorts.

The trunk portion 19 and leg portions 20 of the shorts 10 are constructed in the usual conventional manner and have front portions 21, 22 overlapping one another as at 23 (Figure 3) to provide a so-called open fly front 24. The overlapping portions 21, 22 are secured to the waistband 11 by a row of stitches 25 which also hold in place a cover strip 27 of elongated shape extending up the overlapping portion 22 of the fly front 24.

40 The waistband 11 consists of outer and inner layers of fabric 30 and 31 with elastic material such as rubber threads 32 arranged between them (Figure 3). The waistband 11 is arranged with its fabric layers 30 and 31 shirred, gathered or puckered (Figure 1) so as to permit a great amount of stretch before the fabric becomes taut. These components of the waistband 11 itself are held in position by three rows of stitching 33, 34 and 35 respectively (Figure 2), although a greater or lesser number of rows of stitching may be used as desired.

45 The elastic loop 13 is preferably made from a piece of elastic cord having a loop portion 36 provided with a narrow neck portion 37 where the free portions 38 and 39 of the loop portion

36 come close to one another. The free portions 38 and 39 interconnect the upper ends of arm portions 40 and 41 constituting the sides of said loop 13 and converging upwardly toward one another in an inverted V-shaped arrangement (Figure 2) from their more widely spaced lower ends 42, 43. The latter are anchored to the shorts 10 by stitches 44 passing through the overlapping portions 21 and 22 of the trunk portion 19 of the shorts 10. Thus, the loop 13 is free to expand throughout almost its entire length, except at its lower ends 42 and 43. The cover strip 27 is of elongated shape and is secured to the overlapping portions 21 and 22 by the same row of stitches 25 previously mentioned, and has upwardly converging rows of stitches 45, 46 (Figure 2) which restrict the side-wise expansion of the loop 13 and maintain its neck portion 37. The lower portion of the loop 13 within the converging tunnel-like pocket or heading 47 between the overlapping portion 21 and the cover strip 27 is thus free to expand and is additionally held down by the portion 40 of the lower row of stitching 35 which extends across the cover strip 27. The converging tunnel-like space 47 is roughly triangular in shape and has an opening 49 at its upper end through which the loop 13 projects.

In the use of the invention, the wearer puts on the shorts in the usual way by stepping into the leg portions 20 and drawing the trunk portion 19 upward around his body until the waistband 11 is located approximately at his waistline. Having put on his shirt 15, he hooks the loop 13 over the nearest button 14 on his shirt and then inserts the button 14 through the buttonhole 16 so as to lock the upper portion 36 of the loop 13 in position around the button neck 50 formed by the thread by which the button is attached to the shirt. The neck portion 37 of the loop 13 passes through the space between adjacent buttons 14 and the loop 13 is free to expand almost throughout its entire length from its upper portion 36 to its ends 42 while being held in its loop shape with its narrow neck 37 by the restricting converging rows 45, 46 of stitches. With the loop 13 thus attached to the button 14 or rather to its thread 50, the shirt 15 is held down and the shorts 10 held up. At the same time, the wearer can sit down without the necessity of detaching the loop 13 from the button 14 and may even pull the waistband 11 below the buttocks while in a sitting position without detaching the loop from the button because of the resilience of the long loop. The loop 13, being permanently attached to the shorts, cannot become lost or misplaced and does not require the presence of buttons on the shorts. As previously stated, the cover strip 27 almost completely conceals the loop 13 and at the same time prevents stretching of the waistband 11 at the upper end of the cover strip 27.

What I claim is:

1. In combination with the trunk portion of a man's undergarment having a waistband at the upper edge thereof, an inverted V-shaped loop member of elastic material mounted in the center of the front of said trunk portion, said loop member having arm portions constituting the sides of said loop member, said arm portions having lower ends spaced more widely apart than the upper ends thereof, said lower ends being secured to said trunk portion adjacent said waistband, said loop member also having a closed loop portion interconnecting said upper ends of said arm portions and extending upwardly above said waistband, and a cover strip secured to said trunk portion and extending over said arm portions of said loop member, said cover strip having upwardly-converging securing elements disposed outwardly of the outer edges of said arm portions and forming an upwardly-tapered pocket containing said arm portions and having a top opening through which said loop portion projects upwardly.

2. In combination with the trunk portion of a man's undergarment having a waistband at the upper edge thereof, an inverted V-shaped loop member of elastic material mounted in the center of the front of said trunk portion, said loop member having arm portions constituting the sides of said loop member, said arm portions having lower ends spaced more widely apart than the upper ends thereof, said lower ends being secured to said trunk portion adjacent said waistband, said loop member also having a closed loop portion interconnecting said upper ends of said arm portions and extending upwardly above said waistband, said arm portions of said loop member converging upwardly from said lower ends toward said upper ends, said loop member having a relatively narrow neck portion between said loop portion and said upper ends of said arm portions, and a cover strip secured to said trunk portion and extending over said arm portions of said loop member, said cover strip having upwardly converging securing elements disposed outwardly of the outer edges of said arm portions and forming an upwardly tapered pocket containing said arm portions and having a top opening through which said loop portion projects upwardly.

MEYER HOCHBERG.
